PICTURE FRAME MOULDING

Johannes Vihma, Toronto, Ontario, Canada, assignor to Artistic Woodwork Co. Ltd.

Filed Nov. 27, 1974, Ser. No. 527,647

Term of patent 14 years

Int. Cl. D6—07

U.S. Cl. D6—246

FIG. 1

FIG. 2

FIG. 1 is an end view of a picture frame moulding showing my new design,

FIG. 2 is a perspective front view of the moulding illustrated in FIG. 1,

FIG. 3 is a perspective back view of the moulding illustrated in FIG. 1,

FIG. 4 is a plan view of the underside of the moulding illustrated in FIG. 1.

The moulding is shown broken away at the center in FIGS. 2—4 to indicate indeterminate length.

I claim:

The ornamental design for a picture frame moulding, as shown and described.
